VAULT PROTECTIVE SYSTEM

Clarence D. Ellithorpe, Springfield, N. Y., assignor
to Duplex Electric Company, New York, N. Y.,
a corporation of Delaware

Application February 2, 1934, Serial No. 709,412

16 Claims. (Cl. 20—1.01)

This invention relates to the protection of bank vaults etc., wherein the use of a protective remote control for vault door locks, making necessary the services of two persons to open the vault door, is designed to prevent bandit attack on vaults particularly at opening time in the morning or at any time during the day. It is one of the features of my invention that the person operating the remote control is protected from attack by bandits by an armored guard room in which the remote control is located, and that he is automatically kept prisoner in said guard room for a long enough period to insure against one of the bandits entering the guard room to operate the remote control for the vault door.

Many recent robberies of bank vaults have occurred in the early hours of the morning after the normal time lock on the vault door is released and before normal opening time, namely, from six o'clock in some instances when the time clock releases, to nine o'clock just before the day's business has commenced. These robberies have been especially vexatious for, knowing that the time lock of the usual vault door releases at an early hour so that the bank may be made ready for business at the proper time, bandits have broken in the banking or other room and awaited the arrival of the proper official, or have kidnaped him the night before and then, after the release of the time lock, they have forced the official to unlock the combination lock and open the vault door.

The principal object of my invention is to provide a system of controls for a vault door which requires the services of at least two persons one of whom operates the usual combination locks and the other of whom operates a supplemental locking device by means of a remote control mounted in a bullet proof guard room to prevent bandit attacks especially in the morning and throughout the day. The control guard room door must be closed to operate the remote control, and when the door is closed it is automatically locked for a predetermined period such as two hours so that no bandit will ordinarily enter the guard room to operate the remote controls as to do so would result in his capture.

The guard or bank official who normally enters the guard room to operate the remote control to permit opening of the vault door will be automatically protected from gun fire or other attack by the bandit and will be in a position to cover the entrance to the vault, the banking room and the exits, by suitable firearms which he may discharge through the guard room port holes in

case of bandit attack at opening time or during the day. He will also be provided with suitable alarm signals connecting with the police department or other outside location to warn authorities of any raid or hold-up, and with gas masks to counteract a gas attack. The guard room is normally made only large enough to permit one person to enter the same.

In this way, it will be seen, the bandit attack is completely foiled because the bandits will not have one of their men enter the guard room and be made a prisoner for two or more hours which would result in his capture and eventually the capture of the rest of the bandit gang; neither will they be able to force the cashier or guard to enter the guard room to operate the remote control, for once inside the guard room the cashier or guard will be automatically protected from the bandits and can safely refuse to operate the controls to open the vault door or can send an alarm, or fire out upon the bandits from his protected position. If a bandit should force his entrance into the guard room with the bank official he will be automatically locked therein for two or more hours and neither of them can get out for that time.

As an additional feature of my invention I may provide in a preferred form, a series of controls for the door to the guard room control and for the vault door lock which automatically operate an alarm if an attempt is made to close the guard room door at an improper hour or if the correct sequential operation of the controls for the vault door is not followed. In this way any attempt to operate the controls by an inexperienced person will probably cause an alarm.

Another feature of the invention is to provide control circuits for suitable alarm mechanism in operative relation with the guard room door and with the remote control lock so that any attempt to force the mechanism by the bandits or even by authorized persons will operate the alarms. Safety release mechanism may be provided but it preferably cannot be operated even by authorized persons without sounding an alarm.

As a subsidiary feature of the invention, the guard control room may constitute the teller's cage, for example, rather than be a separate compartment requiring the services of an additional man. In such case as in small banks for example, the vault door would be opened by two people, one operating the remote control lock from within the guard room and the other releasing the combination locks on the vault door, but the teller, being in his cage in this case the

guard room, although locked therein, would still be free to carry on the bank's business with customers. In such an arrangement, the cage would be provided with bandit proof deal trays or other means for receiving and paying out money.

Further objects and advantages of this invention will appear from the following disclosure thereof taken in connection with the attached drawings which illustrate a preferred form of embodiment thereof and in which:

Figure 1 is a partial front elevation of the interior of a bank room having a vault door and armored remote control guard room;

Figure 2 is a horizontal section taken substantially along the line 2—2 of Figure 1;

Figure 3 is a horizontal section taken substantially along the line 3—3 of Figure 1 and showing the air vents;

Figure 4 is a central vertical section taken substantially along the line 4—4 of Figure 1;

Figure 5 is a central vertical section taken at right angles to Figure 4 and showing the control panel door open to expose the controls;

Figure 6 is a horizontal section on a larger scale showing one form of embodiment of the lock for the vault door, operated by the remote control;

Figure 7 is a section through one form of guard room door lock operated by a time clock for keeping the guard room door locked closed for a predetermined time after the guard has entered;

Figure 8 is a partial vertical section showing a modified form of control room door operating means, and;

Figure 9 is a diagrammatic layout of an illustrative wiring diagram.

In the form of embodiment of my invention illustrated herein I provide an armored and bullet proof guard room 10, such as shown in Figure 1, preferably mounted some distance from the vault door 12 which may lead to a bank storage compartment or other safe keeping room. In common practice, especially in banks, the vault door 12 is provided with a time lock (not shown) which prevents the opening of the door until a predetermined hour in the morning; after the predetermined time the door may be opened by an operation of the combination locks 13 and 14 by a person on the outside of the vault familiar with the combination. After the time lock has released and after the combination lock is operated and released, the door 12 may be opened by the use of the handle 15. This is the usual construction of bank vault doors and is well known in the art, and bandits often have availed themselves of this knowledge to force the proper party to open the combination locks 13 and 14 after the release of the time lock in the morning and prior to the arrival of the bank force so that a robbery could be consummated with the minimum of interference and the maximum of results.

In the practice of my invention the vault door 12 is provided with a supplemental lock 16, the details of one form of which are shown in Figure 6. This lock serves the principal purpose of preventing the opening of the door 12 except when the lock 16 is properly released even though the normal time lock and combination lock are released. The supplemental lock may be placed on the inside or outside of the vault door and need not be of unusually strong construction as it is provided with alarm mechanism so that when it is improperly opened or tampered with or de-

stroyed an alarm will sound in the police station or elsewhere as desired.

The supplemental lock 16 is controlled through a suitable remote electrical or mechanical circuit from a guard room 10 which may be of any desired construction but is preferably bullet proof or armored against usual gun fire and is preferably protected in any well known manner such as by electric alarm systems 11, against burglar attack. The door 18 to the guard room is also bullet proof and is preferably cylindrical in shape to facilitate rotation and closure, the door being mounted on suitable rollers 19 for this purpose. The door is also provided with one or more gun ports 20 below suitable bullet proof sight glasses 21 and is arranged to rotate through an angle of approximately 150° so that a guard within the enclosure will be able to cover with gun fire almost any part of the bank. Additional sight glasses 23 and 24 may be provided in the side walls of the guard room. The door is provided with a suitable handle 22 through which it may be swung closed. While I have illustrated a cylindrical shaped guard room with a cylindrical door it will be understood that this shape is not essential and that hexagonal, rectangular or other shaped rooms with swinging doors may be readily used.

The controls for the supplemental lock 16 are arranged so that they cannot be operated except when the guard room door 18 is closed and when the guard room door 18 is closed, it is held closed for a predetermined period such as two or more hours so that any one entering the guard room to operate the controls for the lock 16 will be kept a prisoner for the predetermined period. As the controls within the guard room cannot be operated except by entering the guard room and closing the door, the person in the guard room is protected and is free of any compulsion by the bandits.

One form of apparatus for holding the guard room door 18 closed is shown in Figure 7 and includes a guard room door control 30 which is provided with a gravity actuated latch 33 which contacts with lugs 32 and 32a mounted on the top of guard room door 18 as shown in Figure 3. The latch 33 may be actuated to release position by the solenoids 34 connected by a suitable electrical conduit 35 in a circuit through a time clock 40 hereinafter described which may be set to permit release of the guard room at predetermined intervals.

Two sets of lugs, which are preferably of a wedge or similar shape, are provided to permit locking of the guard room door 18 in either an open or closed position. Lugs 32a are spaced relatively close together and when the door is rotated to a position such that latch 33 will engage both of the lugs, the door 18 cannot be moved except by release of the latch actuating solenoid 34 which is prevented after business hours by means of a circuit hereinafter described which includes contacts on time clock 40. This prevents an unauthorized person from seeking to hide in and close the guard room after business hours anticipating an opportunity, during business hours the following morning, of releasing the supplemental vault door lock 16.

The second set of lugs 32 are spaced from each other so that when the guard room door 18 is closed, it can be moved through the desired angle hereinbefore described. While the door can be closed from a released position, by merely rotating it, nevertheless, it cannot be opened for exit

of the occupant until the latch 33 is raised by actuation of the solenoid 34 and again, by circuit relation controlled by time clock 40, I have arranged for opening of the door only at specific intervals during business hours. This circuit arrangement similarly permits releasing of the door from its locked open position.

The latch 33 is provided with a switch 37, the contacts of which are controlled by the upward movement of the latch and if the door is closed after business hours, it not having been locked open, the switch 37 will operate the general alarm 76. Operation of the controls for the release of supplemental lock 16 is thus restricted to business hours or the alarm would be operated, and the guard room door cannot be opened when once closed except at predetermined periods as described in connection with the operation of the time clock 40.

One form of embodiment of a supplemental lock 16 such as shown in Figure 6, may be provided with a latch 42, which is retracted by the solenoid 43 connected by conduit 25 with certain combination switches 45 and 46 on the remote control panel 26 as shown in Figure 5. The supplemental lock may also be surrounded with suitable heat and drill protection 16a as illustrated diagrammatically in Figure 9, so that any attempted destruction of the lock 16 will also operate alarm 76. Constructions embodying such protection are now well known to the art. A typical example of a suitable construction is described in United States Letters Patent No. 1,041,395, issued on October 15, 1912, to John P. Williams and Hermann Huhn for an "Electro-thermostatic lining for vaults, safes, etc."

The control panel for operating the supplemental lock 16 to release the vault door and for releasing the guard room door control 30 is indicated at 26 in Figure 5. It may be provided with a door 27 which cannot be reached until one enters the guard room 10 and closes the guard room door 18. The door 27 as shown in Figure 2 opens into the guard room through the opening 18a in the door 18 which serves as the entrance to the guard room. The door 27 cannot be opened therefore until the door 18 has been moved to a position where its opening 18a is opposite the control panel 26, and this automatically closes the entrance to the guard room and as one of the lugs 32 on the top of the door passes under latch 33 the latch 33 locks the guard room door 18 closed.

The combination switches 45 and 46 which may be mounted on panel 26 are in suitable circuit relation with the solenoid 43 as hereinafter described, and so arranged that when turned in the proper direction to the proper point the solenoid 43 will withdraw the latch 42 so that the vault door may be opened. If the combination switches 45 or 46 should be turned in an improper sequence or in the reverse direction the alarm 76 will be sounded and if the latch is withdrawn after business hours the switch 81 will also operate alarm 76.

The panel 26 also contains a clock 40 having continuous twenty-four hour operation and provided with circuit opening and closing contacts as hereinafter described (see Figure 9 and description) which are so arranged as to permit proper or authorized use of the guard room and remote controls but so as to operate alarm 76 if the guard room or controls are operated in an improper manner or at an unauthorized time. A circuit is provided so that, should the door 18

not be positively locked by the lugs 32a, closing thereof and consequent movement of latch 33 by a lug 32 after business hours will close the switch 37 and operate alarm 76. A further circuit is provided through the clock 40 so that the guard room door 18, once closed, cannot be opened except by contacting the switch 47 at certain periodic intervals. Preferably the control is such that the door 18 cannot be released except at eight-thirty o'clock, ten o'clock, twelve o'clock, one o'clock, three o'clock, and four-thirty o'clock during the day and only at such periods for approximately five minutes. It will be clear therefore that if anyone goes into the guard room he will be forced to stay in and be kept a prisoner for a particular period of time which in the morning may be two hours and if the guard room is not closed, no opening of supplemental lock 16 is possible. It is clear that no bandit would be willing to take the risk in being held a prisoner for such a long period, nor will a bandit relish having an employee of the bank in a bullet proof guard room where he is protected from the bandits and is free to sound alarm 76, operate a code signal 69, which is described hereinafter, or to shoot at the bandit at will.

The clock 40 is set so as to permit entrance into the guard room under proper conditions without operating alarm 76 between eight o'clock in the morning and five o'clock at night as the vaults are usually kept closed except for short periods during the day when access thereto is necessary. The clock also actuates a periodic warning signal 71 controlled by the reset control 64 which requires the guard to operate the control 64 at predetermined intervals to prevent the sounding of the general alarm 76 thus insuring attentiveness and alertness of the guard so that he can watch the business floor through window 21 while he is locked in the guard room. A buzzer may serve as the periodic warning signal 71 and as described in connection with Figure 9 it is preferably operated at ten minute intervals for ten second warnings to check the vigilance of the guard. At the end of every ten minute period during the time that the guard is within the enclosure, the warning signal 71 sounds, indicating that the general alarm 76 will be sounded if the control 64 is not operated, as hereinafter more fully described. This will be an effective check on the guard and prevent his being incapacitated as by sickness etc., without warning the authorities or bank officials that he is unable to carry out his guard duties.

The time clock 40 cannot be interfered with from the panel as it is preferably mounted behind the panel in a sealed manner so that it may only be changed by destroying the panels which will operate the alarm 76 as fully described in connection with the showing of Figure 9. It will prevent the guard or any other person from tampering and there will be no normal manner by which the guard can get out except under the predetermined circumstances mentioned immediately above or by emergency locks 53 and 53a hereinafter described which when operated, also operate alarm 76.

The panel 26 is provided with suitable telephone jacks 61 or with any other desired telephone or warning controls operated in any desired manner so that the guard may be in communication with other parts of the bank or with police or fire headquarters. He may also have guns, gas bombs, or the like, not shown, stored in

the compartment 26a below the panel 26. The stool 63 will be provided for his convenience.

The guard room 10 is provided with vents 55 shown in Figure 3 which extend up through the back of the enclosure so that the air will circulate as shown by the arrows and will discharge through a suitable conduit 56 which may extend out through the wall and up a suitable flue. It is, of course, to be understood that different forms 10 of ventilation are possible either by perforations around the base or from a channel beneath the floor cooperating with suitable vents in the top. The guard room may be provided with fans for forced draft ventilation so that any gas may be 15 quickly dissipated and a gas mask may be provided for the guard.

One suitable circuit for operating the various 20 electrically controlled parts of the vault protection system is shown in Figure 9. It will be understood, however, that various modifications and changes may be made therein to suit the circumstances of the particular installation. The twenty-four hour clock dial is indicated at 40 and the two combination control switches for releasing 25 the supplemental lock 16 are indicated at 45 and 46. A one hour contact dial operating in conjunction with the clock dial 40, is provided at 49a to give a ten second warning signal every ten minutes throughout the day to insure the alertness 30 of the guard in the guard house. A master gravity ringer relay is indicated at 73 to operate the general alarm 16 which may be located at the police station, fire house or other suitable point outside the bank. Two cylinder key locks 53 and 35 53a are provided for the emergency opening of the guard house by keys, one of which is controlled by the police or fire departments. The lock for the guard room is indicated at 30 and the supplementary lock for the vault door has the latch and solenoid 42, 43, respectively.

The electric thermostatic protection surrounding the supplementary vault door lock parts 42 and 43 is indicated at 16a and the batteries for operating the entire system are indicated at 72. 45 A series of three separate combination controls 47, 60 and 64 for controlling respectively, the release of the guard room door, the operation of a police alarm, and for restoring the operation of the general circuit is generally indicated at 72a. 50 These controls may be located either on the control panel 26 as shown in Figure 5, or in another suitable location, for example, on the inside of the revolving cylinder door for the guard room.

The clock 40 has a raised surface 40c between 55 eight o'clock in the morning and five o'clock in the afternoon which normally represents the open period of the bank. This period may be adjusted in accordance with the routine of the particular bank in which this device is to be installed. Between four o'clock in the afternoon and eight o'clock in the morning the cam of contact 84 60 rides on the lower surface 40d of the dial so that contacts 84 and 85 are closed and through the line 85a, the positive side of the batteries 72 is 65 connected with the contacts 81 and 37 of the supplementary vault door lock 16 and the guard room door control 30 respectively.

If after business hours a robbery is attempted 70 and the supplementary vault door lock 16 is tampered with by drilling or the like, a circuit will be established between the two sides of the protective circuit 16a. One side of this circuit may be grounded to the lock casing, the other connected to an insulated layer of foil or other conductive material embedded in or secured to the

casing. The penetration of a drill to the foil will close a circuit between these two, with these results: The negative side of the battery leads through control 60 and wire B to the solenoid 75. It also is connected, through relay 73 and leads 5 1 and 2 adjacent said relay, to the inner side, as shown in Figure 9, of circuit 16a. Upon closing said circuit 16a, the current from the negative side of the battery is grounded through the outer side of circuit 16a, thus shunting the current 10 from solenoid 75, whereupon the alarm 76 is sounded.

If the guard room door should be moved to closed position from a released position, after business hours, an alarm would be sounded because of the following arrangement: By the actuation of the switch 37 due to movement of the door a circuit would be completed from the positive side of the battery through the wire 85a, the contact 84, contact 85 to the outer side, as shown 20 in Figure 9, of the protective circuit 16a and also to one of the contacts 37, thence through the other contact 37, the coil 73a of the relay 73, the armature 73b and through return wire B to the negative side of the batteries 72. Energization 25 of the coil 73a by the completion of this circuit will release latch 73c allowing armature 73b to fall thus opening contacts 91 which in turn will break the closed circuit of the solenoid 75 which 30 will operate the remote alarm 76.

The closed circuit of solenoid 75 includes wire B to negative polarity of battery 72, thence positive polarity of the battery, through wire 85a, to contacts 91, thence through contacts 95 and 96 or their shunt 64, through safety lock switch contacts 53b and 53c to solenoid 75. Any opening of contacts 91, and any unguarded opening of contacts 95 and 96 will thus open circuit solenoid 75 and operate alarm 16. During business hours however, as shown to begin at approximately eight o'clock in the morning, when the raised surface 40c of the clock engages contact 84, contacts 84 and 85 are opened and 83 and 34 are closed, thus shunting the current from the circuit above described and connecting the positive polarity of the batteries 72 to the contacts 93 and 98. The opening of the contacts 84 and 85 thus permits closing of the guard room door without sending an alarm and also permits the operation of the vault door lock, as switches 37 and 81 are then in open circuit and when either is actuated the circuit to solenoid 75 will not be broken by relay 73 and no alarm will be given. Contacts 86 and 87 are not affected by the position of surfaces 40c and 40d of the clock. They 55 cooperate with specially located lugs 40b on the clock, as described hereinafter.

The guard having entered the guard room and closed the door may then operate the combination switches 45 and 46 to release the supplementary vault door lock 16. The guard in revolving the contact switches 45, 46 clockwise will stop at pre-arranged numbers. At these numbers the contacts 92 and 93 will be connected together, thus connecting the positive side of the battery direct to the contact spring 89 controlled by the switch 46, and the contacts 88 and 89 are connected to complete the circuit through the coil 43 of the supplementary vault door lock 16 70 and to cause the bolt 42 to be withdrawn to release the vault door 12.

The cashier may now open the vault door but the guard cannot come out of the guard room until such time as the dial 40 has advanced to 75

the point where one of the lugs 40b on the dial engages the cam of contact 87 and lifts it into engagement with the contact 86. At this time the positive side of the batteries is connected direct to the control switch 47 in the guard room by means of wire 85a, contacts 86 and 87. Closing the circuit at 47, the guard completes a circuit through the coils of the solenoid 34 back to the negative side of batteries 72 which raises the latch 33 and permits the guard room door to be opened. As soon as that one of the lugs 40b which was in contact with the cam of contact spring 87 has passed said cam the guard room is again locked until the next lug reaches the cam of contact spring 87. As illustrated these release lugs 40b are arranged at ten, twelve, one, three and four-thirty o'clock and at about eight-thirty in the morning so that the guard room door may be moved from locked to released position. These lugs close the contacts 86 and 87 for approximately five minutes so that if the guard does not open the guard room door at the particular period permitted he will remain locked in the guard room until the next lug 40b comes into operation. These lugs may be spaced in accordance with the routine desired in any particular bank and are a part of the clock mechanism mounted in protected position behind the control panel.

If the guard, by accident, or any person not aware of the proper combination for manipulating the switches to open the supplementary lock, should revolve the switches 45 or 46 counterclockwise as they are shown in Figure 9, thus closing the contacts, 93, 94 or 89, 90, a circuit will be completed through the gravity relay 73 opening contacts 91 and thus opening the circuit into the general alarm 76 to cause an alarm at the police station. This result is occasioned by the following arrangement.

Contact 93, during the time contacts 83 and 84 are closed, is in circuit with the positive of the battery 72 through wire 85a. Contact 94 is in direct circuit with relay coil 73a and the other side of relay coil 73a is in direct contact with the negative of the battery 72 through wire B. Any counterclockwise rotation of switch 45 will close a circuit through contacts 93 and 94 and thus cause an alarm. If switch 45 were properly turned to close contacts 92 and 93 and switch 46 turned counterclockwise to close contacts 89 and 90, an alarm will also be sounded as contact 90 is connected to relay coil 73a and contact 89 is connected to contacts 92 and 93 and thus to the positive of battery 72 as before.

The periodic warning signal operated by the auxiliary dial 40a, which revolves continuously, comes into operation about eight o'clock in the morning when the raised surface 40c of the dial 40 raises the spring 99 into contact with the spring 98 connecting the positive side of the batteries direct to the warning signal, in the present embodiment a buzzer, 71. The revolving of the dial 40a completes a circuit through the buzzer 71 every ten minutes or each time a lug 40e contacts with contact 97 thus causing the buzzer to operate. The circuit includes wire 85a from the battery, contacts 83 and 84, 98 and 99, buzzer 71, contact 97, lug 40e and thence through wire B to the negative side of the battery. As soon as the buzzer 71 operates the guard will push the reset control 64 to prevent the sounding of the main alarm 76, thus showing that he is alert. If for any reason the reset control 64 is not operated to keep the police alarm circuit closed, then the

lug on the dial 40a will open the police alarm circuit by opening contact springs 95 and 96. The closing of the reset control 64 produces a shunt across the contact springs 95 and 96 and if this control is held closed as long as the buzzer 71 sounds it prevents the opening of the police alarm circuit and the sounding of the police alarm. 5

A code control indicated at 60 for arbitrarily operating the police alarm is in the form of a normally closed contact switch on the negative side of the batteries. Control 60 may be operated to open the circuit controlling the police alarm, which causes the alarm to operate. Such operation, however, does not cause the alarm to be energized through the gravity relay 73 since the control 60 directly interrupts the flow of current from batteries 72 to solenoid 75 through wire B. As a result, control 60 may be used selectively by the guard for the transmission of a code signal 20 to the police station using a pre-arranged code.

The emergency release locks for releasing the guard room door in the event of fire, illness of the guard, or other emergency are indicated at 53 and 53a and are arranged on the outside of 25 the guard room, see Figure 2. They are connected in series, so that the clockwise turning of either of these locks will immediately operate the police alarm, but both locks 53 and 53a must be operated in order to unlock the guard room door 30 in advance of the time set by the lugs 40b on the dial 40. These locks are optional and may or may not be included in the device.

The operation of the lock 53 will move the contact 53b to the right thus closing the circuit to 35 the general alarm 76 by breaking the circuit through solenoid 75 and energizing the contact 53c so that when the lock 53a is operated to move the contact 53c to the right, the circuit is made through the line 53d to the door release 40 switch 41 and thence through the solenoids 34 of the guard room door control 30. It is apparent that instead of running line 53d through the door release switch 41, which requires the co-operation of the guard within the guard room, 45 this line might be connected directly with the solenoids 34 so that the closing of a circuit therethrough would directly energize the guard room control 30 and release the latch 33.

The wiring for the telephone circuit from the jacks 61 for telephone connections between the guard room and the various teller's wickets or at the police station has not been shown and only the simplest open type circuits for operating the various alarms and releases have been indicated 55 to illustrate my invention. It will be understood, however, that multiple clocks may be provided to eliminate the possibility of failure of the system to operate at the proper time and all important circuits and controls may be supervised by closed 60 circuits to prevent failure of operation. The switches 45 and 46 will be of a combination lock type requiring that the dials be turned to two or more numbers before the circuit conditions described are obtained. The circuit connecting 65 these switches with the vault door lock 16 may be also provided with a time delay mechanism, not shown, so that even if the guard has properly operated the switches in the guard room the cashier cannot open the vault door for a period 70 of at least fifteen minutes. Such a time delay mechanism provides an additional protective feature in the event of a hold-up. It is not inconceivable that a guard in the guard room might be persuaded to actuate the lock controls within his 75

reach. Furthermore, it might occur that the guard, due to excitement or for other reasons, would fail to send a police alarm after actuating the lock controls. If, under such circumstances, 5 a substantial delay be required before the vault door may be opened, an additional safeguard would be provided, since a successful attempt at robbery must be executed quickly, and such a delay would enable assistance to be obtained by 10 other means than the aforementioned police alarm system.

It is contemplated that the guard room 10 will 15 constitute an armored and electrically protected enclosure adjacent the vault door. It may, however, be fixed or mounted on rollers and movable into various positions for the wiring. Furthermore, it may be provided in combination with a teller's bullet-proof cage which would 20 also be provided with bullet-proof package receivers and deal trays, so that when the teller or paymaster takes up his position for the day's business he will also be in position to control the opening of the vault door as well as being 25 an armed guard for the rest of the bank. The specific location of the guard room is not material except that it should be in a position so that the guard may cover with his firearms the entrance to the vault, the banking room entrances and as much of the bank as possible. It is of 30 course, not necessary to limit the shape of the enclosure to a cylindrical form, although the cylindrical form has particular advantages in that the door may be revolved to facilitate shooting.

It is expected that under normal circumstances 35 the bank officer or other employee designated will enter the enclosure prior to the commencement of business where he will take up his position as guard and will cooperate with the proper officials to release the vault door after the other 40 official has properly opened the combination locks. Any attempt at that time to rob the vault will be frustrated as the guard will be protected and can safely refuse to release the supplementary lock. He will also be provided with suitable 45 firearms, and with central station alarm sounding means the switch 60 which he will not hesitate to operate as he is not subject to an attack. In an attack the door 18 would be moved around as necessary and although it might be necessary 50 to close the panel door 27 in order to allow free movement of the door 18, this would not be objectionable as the alarm would probably have been previously sounded. It may also be found desirable to place the switch controls 47, 60 and 55 64 on the guard room door so that they will always be available.

Under such normal circumstances in which the bank would usually be opened at approximately eight o'clock in the morning, the guard who was 60 imprisoned within the guard room would be held for only two hours, for example, or until ten o'clock. After that time, if he so desired, he could operate the guard room control 47 and release himself from the enclosure.

If under abnormal conditions, such as kidnaping of a bank officer, a bandit should enter 65 the guard room he would similarly be locked within the guard room for the period of time designated and would be captured. Knowing this 70 the bandits would hesitate to have one of their number enter the guard room, as the capture of one member of a band usually leads to the identification and capture of the entire band.

It is apparent from the foregoing that the 75 circuits and arrangements controlled by the guard

room control 47, the code control 60, and the reset control 64 provide useful protective facilities. The occupant of the guard room is positively protected against opening of the guard room door except at predetermined intervals 5 when the circuit is properly set for such opening and when he has actuated the control 47. In case of robbery or other trouble, he is free to actuate the code control 60 and thus to sound a police alarm without the knowledge of persons around the guard room. His continued attention to duty is maintained by the requirement that the reset control 64 be actuated at ten minute intervals to prevent the sounding of a police alarm.

The guard room 10 is preferably so wired and protected electrically as diagrammatically shown at 11, in Figure 9, that no felonious attempts will be made either to open the room when occupied or to cut an opening in the door at night so 15 that one bandit could get in or out of the guard room when the time lock was released in the morning. The usual well known thermostatically active mats of lead foil and other well known materials which are destroyed by heat or drilling such as those shown and described in Letters Patent No. 1,041,395, hereinabove mentioned, can be used for this purpose. Such material will also be used for the supplemental lock as indicated diagrammatically at 16a in Figure 9.

If desired, the guard room may be operated by other means such as shown in Figure 8. In this case the door 65 is controlled through a wheel and gear 66 and 67 so that the occupant will be able to shut the door under increased power. 30 This may be necessary particularly with heavy doors even though they are provided with rollers 19.

It may be desirable to provide two or more guard rooms in such position to command the 40 entire banking room for protection and it may be desirable to have them arranged so that the controls are interlocking and all respective guard rooms would have to be occupied by the assigned guard before the controls for the vault door could be opened. This may be of particular benefit in 45 large banks and trust companies and it may also be desirable for organizations other than banks where there are two and three vaults each of which must be separately controlled.

In any event it is necessary to have at least two 50 people for opening the vault door, one of whom is locked in a bullet proof and temporarily unopenable enclosure. A mechanical system of interlinked controls may be provided whereby the throwing of the vault door bolts may only be 55 accomplished after the guard room door is closed and a time period had elapsed. In a similar manner, the guard room door could only be opened when the vault door bolts were in locked 60 position. The supplemental lock 16 may be built 65 in the vault door 12, as an additional locking dog on the usual bolt mechanism where new installations are made. Such a mechanism could be readily operated either by electric, pneumatic, hydraulic or mechanical means, such operating means being controlled from within a guarded enclosure which is held in locked position for a predetermined time, the controls being accessible only when the enclosure is locked closed. It is of 70 course to be understood that specific reference to a bank vault and its operating conditions of time of day, etc., are only for purpose of example and that other installations requiring different time periods etc., will have the controls 75

set for periods of business hours and after business hours which may readily be accomplished by variations of the time clock setting.

While I have shown a preferred form of embodiment of my invention I am aware that other modifications may be made thereto and I therefore desire a broad interpretation of my invention within the scope and spirit of the description herein and of the claims appended hereinafter.

I claim:

1. In combination with a lock for a vault door, a remote control for said lock, an armored enclosure for said remote control, entry means for said enclosure, and means to retain said entry means closed for a period of time, said remote control for said lock being operable only when said entry means are in closed position.

2. In combination with a supplemental lock for a vault door, a remote control for said lock, a guarded enclosure for said remote control, entry means for said enclosure and means to retain said entry means closed for a period of time, said remote control for said lock being operable only when said entry means is in closed position, means to sound an alarm, and means to automatically operate said alarm sounding means by an erroneous operation of said remote control.

3. The system of controlling a vault door having a supplemental lock which comprises providing a remote control for said supplemental lock, said control being mounted on a panel in an armored room, and rendered inaccessible by the entrance door to said room, said control being operable when exposed by the closed door of the armored room, and means to hold the armored room door closed for a predetermined time.

4. In combination with a supplemental lock for a vault door, a remote control for said lock, a guarded enclosure for said remote control, entry means to said enclosure and means to retain said entry means closed for a period of time, the remote control for said lock being operable only when said entry means are in closed position, means to operate a warning signal if said remote control is erroneously operated, and means to operate said warning signal if said supplemental lock is released by any but the remote control.

5. A remote control for a bank vault door lock which comprises means to release the lock from the remote point, means at the remote point out of the operator's control to prevent the operator of the control means from leaving the control means for a predetermined period of time after the operation of said lock releasing means and means operative to render the last recited means inoperative after such period of time.

6. A remote control for a supplemental vault door lock including an enclosure for a control panel, means on said panel to release the supplemental vault door lock, means to prevent the operator from withdrawing from said enclosure except after a predetermined period from the time of operating the control means, said enclosure being in position to control the physical ingress and egress of a person to the vault.

7. A system of burglar proof controls for a vault which includes a lock on the vault door, a remote control means remote from the lock for opening the lock and means beyond the control of the operator to prevent the operator of the remote control means from leaving the remote control means for a predetermined period of time.

8. In a means for protecting a vault door having the usual time lock and combination locks,

a supplemental lock, means remote from the lock for opening said lock, and means beyond the control of the operator to imprison the operator of said remote means for a predetermined time, whereby the services of two persons are required for opening the vault door.

9. In combination with means for protecting a vault door, having the usual time lock and combination locks, a supplementary lock, a remote control means for opening said lock, a guard room enclosing said remote control means, means to prevent operation of said remote control means until a person has entered said guard room and closed the door, and means to lock said door for a predetermined period of time, whereby the person entering said guard room to operate the remote control is kept a prisoner for a predetermined time.

10. In combination with means for protecting a vault door, having the usual time lock and combination locks, a supplementary lock, a remote control means for opening said lock, an armored guard room enclosing said remote control means, said guard room having an entry door; means to prevent operation of said remote control means until a person has entered said guard room and closed the guard room door, means to lock said guard room door for a predetermined period of time after the guard room has been entered, and means to prevent closure of said guard room door during unauthorized hours.

11. In combination with a supplemental lock for a vault door, a remote control for said lock, a guarded enclosure for said remote control, said guarded enclosure having an entrance door, a lock for said door, means to rotate said door through a substantial angle, means connected with said lock to prevent the opening of the door for a predetermined time after it is closed, and means to release the door lock, said remote control being operable only when the entrance door is closed.

12. In combination with a supplemental lock for a vault door, a remote control for said lock, a guarded enclosure for said remote control, said enclosure having an entrance door, a lock for said door, said door being rotatable through a substantial angle, means causing said lock to prevent opening of the door for a predetermined time after it is closed, means to release the door lock to allow rotation of said door, said remote control being operable only when the entrance door is closed, and means to sound an alarm if said door is closed except at predetermined periods.

13. In combination with a supplemental lock for a vault door, a remote control for said lock, a guard room including a door for said remote control, a lock for said door, said door being rotatable, means to prevent opening of the door for a predetermined time after it is closed, and a control panel within said guard room and containing the remote control, and means to operate a warning signal if said door is closed except during predetermined hours.

14. In combination with a lock for a vault door, a remote control for said lock, a guard room for said remote control, an entrance door to said guard room, said door being rotatable, a lock for said door, means to delay opening of the door for a predetermined time after it is closed, a control panel within said guard room having remote control operating means, and means to operate a warning signal if said guard room door is closed except during certain predetermined hours, said

65
60
70
75

means being operable if the vault door is opened at any but predetermined hours.

15. In combination with a lock for a vault door, a remote control for said lock, a guard room for said remote control, said remote control being carried on a panel within said guard room, a means on said control panel to release the vault door lock including a combination switch, warning means operated by the false operation of said combination switch, an entrance door for said guard room, and means to prevent opening of the guard room door for a predetermined time after it is closed.

16. In combination with a lock for a vault door, a remote control for said lock, a guard room for said remote control, said guard room having a movable door, a lock to lock said guard room door and means to prevent opening of the lock 5 for a predetermined time after the guard room door is closed, said guard room having a control panel operable only when said guard room door is closed, means on said control panel to release the vault door lock including a combination 10 switch, and warning means operated by the false operation of said combination switch.

CLARENCE D. ELLITHORPE.
